US0D1062222S

(12) **United States Design Patent** (10) **Patent No.:** **US D1,062,222 S**
(45) **Date of Patent:** **** Feb. 18, 2025**

(54) **CARD HOLDER**

(71) Applicant: **Haiwei Zhiyuan Technology (Shenzhen) Co., Ltd**, Shenzhen (CN)

(72) Inventor: **Hua Zhang**, Shenzhen (CN)

(73) Assignee: **Haiwei Zhiyuan Technology (Shenzhen) Co., Ltd**, Shenzhen (CN)

(**) Term: **15 Years**

(21) Appl. No.: **29/879,863**

(22) Filed: **Jul. 13, 2023**

(30) **Foreign Application Priority Data**

May 23, 2023 (CN) 202330305382.9

(51) **LOC (15) Cl.** **03-01**

(52) **U.S. Cl.**

USPC **D3/247**; D3/249
